UNITED STATES PATENT OFFICE.

EDWIN S. PRIDHAM AND PETER L. JENSEN, OF OAKLAND, CALIFORNIA, ASSIGNEES
TO THE MAGNAVOX COMPANY, OF OAKLAND, CALIFORNIA, A CORPORATION OF
ARIZONA.

MOVABLE COIL FOR ELECTRODYNAMIC RECEIVERS.

Application filed May 10, 1922. Serial No. 559,751.

To all whom it may concern:

Be it known that we, EDWIN S. PRIDHAM and PETER L. JENSEN, citizens of the United States, residing at Oakland, county of Alameda, and State of California, have invented new and useful Improvements in Movable Coils for Electrodynamic Receivers, of which the following is a specification.

10 This invention relates to movable coils for electro-dynamic receivers.

A receiver of the type under consideration is illustrated and described in our application, Serial No. 377,354, filed April 15 28th, 1920, of which the present application is a continuation and improvement.

The receiver comprises generally an electro-magnet having concentric pole pieces with a circular coil disposed in the annular 20 space between the pole pieces, said coil being rigidly attached to the diaphragm of a sound box. The object of the present invention is to simplify and improve the construction, operation and assembly of a movable coil of this type.

One form which our invention may assume is exemplified in the following description and illustrated in the accompanying drawing, in which—

30 The figure shows a central sectional view of the upper portion of a receiver embodying our invention.

So much of the magnetic structure as is necessary to an understanding of the invention is shown herein and includes an iron 35 casing 10, a core 11 within the casing and a winding 12 for the core. The core terminates in a pole piece 13 and a plate 14 fitted upon the casing and provided with a circular opening to surround the pole piece 13 40 constitutes an outer pole piece. These pole pieces should be carefully spaced so as to leave a true annular space for the reception of the movable coil.

45 This coil comprises a ring-shaped frame 15 of insulating material formed with a depression 16 to receive a winding 17. This winding consists of a large number of turns of very fine wire. The coil is rigidly connected to a diaphragm 18 of a sound box by means of a bracket 19. This bracket is somewhat cone-shaped in form with its sides cut away, leaving three or more legs 50

20. The legs each have a small integral lug

21 at their lower ends to enter a small opening 22 in the insulating frame of the coil for connecting the parts together. The apex or top portion 23 of the bracket is provided with a central opening through which a screw 24 passes for connecting the same to 60 the diaphragm, the screw being preferably provided with a nut 25.

Since the coil vibrates freely, it is important to bring the leads into the coil in such a way as to avoid breakage and this we accomplish by connecting the ends of the coil by soldering or otherwise to flat metallic conducting strips 26, which are led along the legs of the bracket and across the lower face of the diaphragm to the outer edge 70 thereof, where they connect with binding posts 27. The metallic strips are laid between two adhesive tapes 28 and by means of these adhesive tapes the conducting strips are held in place on the bracket and diaphragm. Inasmuch as the vibration at the periphery of the diaphragm is comparatively small, the conducting strips are not subjected to the liability of breakage as they would be if they extended directly out 80 from the movable coil to the stationary posts.

In assembling the coil, the bracket is connected to the frame thereof by slightly compressing the legs to bring them within the frame so that the lugs 21 enter the openings in the frame. Then the legs are spread and the lugs bent over to retain the parts together. The bracket is thereafter connected to the diaphragm and the latter is 90 positioned on the sound box to bring the movable coil into proper position within the annular space between the poles. We find that a bracket, such as shown herein, having a somewhat conical shape affords the desired rigidity and, furthermore, the open sides are important, since an enclosed connecting member or bracket in this location would impair the value of the tones given off by the diaphragm.

Having thus described our invention, what we claim and desire to secure by Letters Patent is:

1. In an electro-dynamic receiver, an inner cylindrical pole piece, an outer pole piece 105 having a cylindrical opening surrounding and spaced from the inner pole piece, a circular coil positioned within the annular

space between the pole pieces, said coil comprising an insulating frame having a large number of turns of fine wire wound upon its exterior, a flexible diaphragm and means for rigidly connecting said frame to the diaphragm, said connecting means comprising a conical member cut away at its sides to form legs, said legs fitting within the frame and each having an integral lug to enter an opening in the frame and means for connecting the apex of the bracket to the central portion of the diaphragm.

2. In an electro-dynamic receiver, an inner cylindrical pole piece, an outer pole piece having a circular opening surrounding and spaced from the inner pole piece, a circular coil positioned within the annular space between the pole pieces, said coil comprising an insulating frame having a large number of turns of fine wire wound upon its exterior, a diaphragm, a bracket having a plurality of legs extending from the insulating frame up to the diaphragm for rigidly connecting the coil thereto, and means for electrically connecting the coil to the stationary binding

posts comprising conducting strips adhesively secured to the legs of the bracket and to the under surface of the diaphragm.

3. In an electro-dynamic receiver, an inner cylindrical pole piece, an outer pole piece having a circular opening surrounding and spaced from the inner pole piece, a circular coil positioned within the annular space between the pole pieces, said coil comprising an insulating frame having a large number of turns of fine wire wound upon its exterior, a diaphragm, a bracket having a plurality of legs extending from the insulating frame up to the diaphragm for rigidly connecting the coil thereto, and means for electrically connecting the coil to the stationary binding posts, said means comprising a pair of adhesive strips for each end of the coil applied to the legs of the bracket and to the under side of the diaphragm and a conductor carried between each pair of adhesive strips.

EDWIN S. PRIDHAM.
PETER L. JENSEN.
